US00D831071S

(12) **United States Design Patent** (10) **Patent No.:** **US D831,071 S**
(45) **Date of Patent:** **** Oct. 16, 2018**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Jay Christopher Capela**, Santa Cruz, CA (US); **Alexander Charles MacLean**, San Jose, CA (US); **Parthiban Mohanraj**, Cupertino, CA (US)

(73) Assignee: **Apple Inc.**, Cupertino, CA (US)

(**) Term: **15 Years**

(21) Appl. No.: **29/605,219**

(22) Filed: **May 24, 2017**

Related U.S. Application Data

(63) Continuation of application No. 29/546,682, filed on Nov. 24, 2015, now Pat. No. Des. 791,831, which is a continuation of application No. 29/485,374, filed on Mar. 18, 2014, now Pat. No. Des. 747,728.

(57) **CLAIM**

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE shows a display screen or portion thereof with graphical user interface showing our new design.

The peripheral dashed broken lines illustrate a display screen or portion thereof and form no part of the claimed design.
